UNITED STATES PATENT OFFICE.

CLAUDE R. SIMMS, OF FLEMING, COLORADO.

CHECK-PROTECTOR.

1,335,201.

Specification of Letters Patent. Patented Mar. 30, 1920.

Application filed September 18, 1918. Serial No. 254,576.

To all whom it may concern:

Be it known that I, CLAUDE R. SIMMS, a citizen of the United States, residing at Fleming, in the county of Logan and State 5 of Colorado, have invented certain new and useful Improvements in Check-Protectors, of which the following is a specification.

This invention relates to impressing or penetrating machines, and more especially 10 to those in which the type wheel is rotary; and the object of the same is to produce an improved form of check protector wherein the check is pushed forward a distance corresponding to the length of the word em- 15 bosSED or printed thereon.

Another object is to simplify the general structure of the machine and reduce its cost of manufacture so as to put it in the reach of all.

Yet other objects will be described as the following specification proceeds, and reference is made to the drawings herewith and in which:

Figure 1 is a front elevation,
Fig. 2 a plan view,

Fig. 3 a rear elevation with the casing removed,

Figs. 4 and 5 are vertical sections on the lines 4—4 and 5—5 of Fig. 3, and

Fig. 6 a perspective detail of the platen and its operating mechanism.

On a suitable base 1 is mounted a housing 2 consisting of a casing shaped to fit closely over the parts yet to be described and to present a pleasing appearance, and parts of this housing will be removable as usual in machines of this character in order that access to the interior mechanism may be had. Toward the front the housing has a drum 3 having an opening in the top as at 4 for a purpose yet to be described, and a hinged door 5 to give access to the inking mechanism. To the right of this drum is a table 6 with a flange 7 upstanding from its rear edge and an adjustable gage 8 at its right edge, and it is upon this table that the check is laid against the flange and fed to the left into the opening 9 best seen in Fig. 4; here it passes under the type wheel and over the platen, and finally it is engaged by the feed rollers in a manner yet to be described. For checks of different widths or when it is desired to print the inscription at different points thereon, the feed table may be adjusted by a screw 10 swiveled in bearings 11 and having a knob 12 at its front end

the screw engaging a nut 13 beneath the table.

On a shaft 20 is journaled a type wheel 21 having characters on its periphery as 60 best indicated in Fig. 3 for printing words designating numbers if this device is to be used for marking checks. Short words such as one and six would of course require only three letters, whereas long words such as 65 seventeen would require characters leading a considerable distance across the periphery of this type wheel, and therefore said periphery must be made as wide as the length of the longest word. I will here say that 70 the working face of the type may be serrated or otherwise roughened so as to embed the paper of the check being printed and the working face of the platen will then be correspondingly formed as shown in Fig. 6. 75 Ink may or may not be used as desired. If it is used, rollers 22 supplied constantly with ink from a suitable fountain 23 will bear on some part of the type wheel so that the type surface will be constantly inked 80 and such as are thrown into contact with the check will therefore print thereon, besides embossing or imprinting. Fast on the shaft 20 is a gear 24 meshing with another gear 25 which is fast on a rear shaft 30 as seen 85 in Fig. 4. The two gears are of the same size, so that the two shafts 20 and 30 rotate in unison and in opposition; and the rear shaft 30 carries a wheel 33 having notches 34 in its periphery corresponding with the 90 lines of type on the type wheel. Also an important feature of this invention lies in the fact that each notch is of a depth corresponding with the length of the word which stands at the bottom of the type 95 wheel when the notch in question is at the top of the notched wheel, the purpose being set forth below.

A hand lever 40 is fast on a shaft 41 which carries a gear sector 42 within the housing 100 meshing with teeth 43 in an upright plunger 44, the same being guided through the frame work 16 as at 45. On this plunger is a finger 46 so disposed that it engages the uppermost notch 34 in the wheel 33 when 105 the plunger descends under the action of the hand lever 41, but a spring 47 restores the plunger to its raised position and the hand lever to normal when pressure on the latter is released. At the left end of the shaft 20 110 is a knob 48 best seen in Figs. 1 and 2, and when the type wheel 21 is turned by this knob

so that an indicating figure appears through the opening 4, the operator knows that the type word corresponding to that figure is at the bottom of the type wheel. When now 5 the hand lever 40 is moved, the sector 42 causes the descent of the plunger 44 and its finger 46 moves into the appropriate notch 34; and thus it will be seen that the descent of the plunger is proportional to 10 the length of the word about to be printed.

The feed mechanism consists of an upper or presser roller 50 carried by a spring-pressed hand lever 51 at the left end of the opening 9 as seen in Fig. 1, and a lower 15 mechanically operated roller 52 which is fast on a shaft 53 as seen in Fig. 5, as usual. Bevel gears 54 connect the shaft 53 with a cross shaft 55 journaled in the framework 16 directly beneath the rear shaft 30 as best seen in Figs. 3 and 5, and a ratchet 20 56 on the shaft is engaged by a spring-pressed pawl 57 to prevent a retrograde movement thereof.

The feed mechanism is actuated by the 25 rise of the plunger. The latter toward its lower end is provided with teeth 63 engaging a gear 62 mounted loosely on the cross shaft 55 and constituting one element of a clutch. The contiguous element 61 is 30 slidably mounted on the shaft and splined thereto in any appropriate manner, as by having a pin passing through a slot in the shaft as seen in Fig. 3, and the contiguous faces of these two elements are provided 35 with ratchet teeth 60. Springs 64 press the elements normally toward each other so that the ratchet teeth on the adjacent faces are held engaged by yielding pressure. The disposition of the teeth 60 is such that on 40 the descent of the plunger the gear 62 rotates idly past the element 61, and the latter and the shaft 55 will not be turned on account of the pawl and ratchet mechanism 56, 57; but on the ascent of the plunger the 45 ratchet teeth 60 engage the clutch, when the cams permit the teeth 60 to engage each other, the shaft 55 is turned at a distance equal to the rise of the plunger. This in turn rotates the shaft 53 and the feed roller 50 52 a corresponding distance. Thus it will be seen that if the finger 46 had been moved downward into a long slot for the word seventeen for instance, the subsequent rise of the plunger and rotation of the feed mechanism 55 would be considerable and the printed check would be moved along under the type wheel a distance corresponding to the length of so long a word.

The printing is performed by the upward 60 movement of the platen 70. This element is mounted on two arms 71 pivoted at 72 in the framework 16, and connected at their rear ends by a cross rod 73 from which rise links 74 connected in turn at their upper 65 ends to shaft 30, and other links 76 extend

thence forward and are pivoted directly on the shaft 20, so as to cause the shaft 30 to rise and fall through an arc in rear of the plunger and in slots 75 in the frame 16. A spring 78 connects said plunger with the 70 center of the cross rod 73 as shown. Now when the plunger is moved downward under impulse of the handle lever 40, tension is put onto this spring 78 and the entire structure shown in Fig. 6 is moved. The result 75 is that the platen 70 rises and the head is forced upward against the type which will be clear. This occurs while the finger is entering and passing downward in the proper notch 34, and is therefore holding 80 the type wheel stationary while the printing takes place. On the upward movement of the finger during the return movement of the plunger, the tension of the spring 78 is released and the forward feed of the check 85 is permitted in a manner already described.

The foregoing description and the drawings have reference to what may be considered the preferred, or approved form of my invention. It is to be understood that I may 90 make such changes in construction and arrangement and combination of parts, materials, dimensions, et cetera, as may prove expedient and fall within the scope of the appended claims.

Having thus fully described my invention, what I claim as new and desire to secure by Letters Patent, is:—

1. In a device of the class described, the combination with a type wheel and means 100 for setting it manually, a platen, and a pivoted support therefor; of an upright plunger mounted in guides, means for holding it normally raised, means for depressing it manually, and a spring connecting the plunger with the platen support.

2. In a machine of the class described, the combination with a manually set type wheel having dies of different lengths on its periphery, a platen, a vertically movable plunger, means holding it normally raised, a hand lever for depressing it, and connections between it and said platen; of a finger on the plunger, a wheel having notches in its periphery corresponding with the length of 115 said dies adapted to receive said finger, gearing connecting this wheel with the type wheel, teeth on said plunger, a clutch element engaging said teeth, a shaft on which it is loosely mounted, a second clutch element splined on said shaft and spring-pressed toward the first element, a feed 120 mechanism, and connections between said shaft and mechanism.

3. A device of the class described, the 125 combination with a type wheel and means for setting it manually, a platen, and a pivoted support therefor; of an upright plunger mounted in guides, a spring for holding said plunger normally raised, means for 130

depressing it manually, and means for connecting the plunger with the platen support.

4. A device of the class described, the combination with a type wheel and means for setting same, a platen, a frame for pivotally supporting said platen, said frame consisting of a pair of parallel arms, the ends of said arms being attached to a rod, links connecting said rod to the main supporting shaft; of an upright plunger mount-

ed in guides, means for holding it normally raised, means for depressing it manually and a spring connecting the plunger with the platen support.

In testimony whereof I affix my signature in presence of two witnesses.
